HIS ATTORNEY.

UNITED STATES PATENT OFFICE.

ARTHUR E. PETERS, OF LITTLETON, COLORADO, ASSIGNOR TO INGERSOLL-RAND COMPANY, OF JERSEY CITY, NEW JERSEY, A CORPORATION OF NEW JERSEY.

AIR-LINE OILER.

Application filed September 9, 1927. Serial No. 218,466.

This invention relates to oiling devices, but more particularly to an air line oiler adapted to be attached to the air line whereby pressure fluid is being conveyed to machines intended to be actuated thereby.

The objects of the invention are to supply lubricant in suitable quantities and form to rock drills and other similar machines through the medium of the pressure fluid whereby such machines are actuated, to enable such lubricant to be introduced into the pressure fluid supply in any of the various positions which the oiler may assume in practice, and to render the oiler readily adjustable so that the amount of lubricant supplied to the pressure fluid may be varied with respect to immediate requirements.

Other objects will appear hereinafter, and to all of these ends the invention consists of the combination of elements and arrangement of parts having the general mode of operation substantially as hereinafter described and claimed and illustrated in the accompanying drawings, in which

Figure 1 is a sectional elevation of an oiler constructed in accordance with the practice of the invention taken through Figure 2 on the line 1-1 looking in the direction of the arrows,

Figure 2 is a plan view partly in section taken through Figure 1 on the line 2-2 looking in the direction indicated by the arrows,

Figure 3 is a transverse view taken through Figure 1 on the line 3-3 looking in the direction indicated by the arrows, and

Figure 4 is a perspective view of the pendulum body and its bearing.

Referring more particularly to the drawings, the invention comprises a casing A and a cover B secured to the casing by means of stud bolts C and nuts D. The casing A is preferably of substantially cylindrical form and the bottom E of the casing in this instance is concaved so that the outermost edge of a reservoir F within the casing A may lie at a lower elevation than the central portion of the bottom E. The cover B carries on its inner surface an annular shoulder G which projects into the reservoir F and cooperates with the wall thereof for the purpose of centralizing said cover with respect to the casing.

On the top surface of the cover B is formed an enlargement H which extends in this instance at its ends beyond the sides of the cover

B. In the enlargement H is formed a passageway J threaded at its ends to receive the threaded ends of an air line K through which pressure fluid may be conveyed from a suitable source of supply to a drill or other machine intended to be actuated thereby. The passageway J in this instance is in the form of a Venturi tube and accordingly has a restricted portion L in this instance located about midway between the flared ends O of the passageway J.

Means are provided for enabling the conveyance of the lubricant from the reservoir F into the restricted portion L of the passageway. These means comprise a spindle P threaded into the cover B and of such length that its free end extends to a point near the raised portion of the bottom wall E. In this spindle P are formed two longitudinal passages Q and R for conveying pressure fluid into the casing and oil therefrom respectively. The passage R in this instance extends from the inner end of the spindle P to a point near the front end thereof while the passage Q is of somewhat less length and is closed at both ends.

Disposed rotatably on the free end of the spindle P is a bearing S in which is formed a passage T adapted to register with the passage R in the spindle and a passage U registering in all positions of the bearing S with the passage Q in the spindle.

The bearing S is in the form of a flat plate having two cylindrical opposed surfaces V which cooperate slidably with corresponding surfaces W formed in a body X of a pendulum member Y.

The body X in this instance has end slots Z through which the ends of the bearing S may extend and the slots Z are preferably of such width that the pendulum Y may move freely on the bearing S and at the same time prevent leakage of oil between the cooperating surfaces of the bearing and the walls of the slots Z.

Although the bearing S is intended to rotate freely on the spindle P, said bearing is preferably held against endwise movement. The means provided in this instance to prevent such movement consist of a shoulder b on the end of the spindle P, which bears against the front end of the bearing S to prevent movement of the bearing in a forwardly direction. Preferably a washer c is disposed between the rearward end of the

bearing and the cover B to prevent such movement of the bearing in a rearwardly direction.

The pendulum Y is preferably of a length 5 to enable its free end to at all times reach to the lowermost point of the reservoir F in the various positions which the oiler may occupy in practice. To induce rotation of the pendulum Y to the desired position, the free end 10 of said pendulum is in the form of an enlarged head d tapered towards its free end to enable the inlet opening of a passage e in the pendulum to reach the lowermost point in the reservoir. The passage e is intended to convey 15 lubricant from the reservoir and registers with the passage T in the bearing, a groove f being formed in the body X to insure such communication between these passages.

To the end that pressure fluid under maximum 20 pressure may be introduced into the reservoir F to act on the oil within said reservoir and thus force said oil through the various passages provided, a passage g formed in the cover B has an inlet port h opening into 25 a flared end O of the passageway J and with its other end communicates with the passage Q through a port j. Such pressure fluid may then pass through these channels through the port U in the bearing S and thence through a 30 tube k secured in the uppermost portion of the body X and extending to a point near the outer wall of the casing A.

Suitable means are provided for controlling 35 the volume of oil which may be delivered from the reservoir into the passageway J as well as to introduce the oil at a point in the passageway substantially coaxial therewith. To this end a plug o is disposed in a bore p in the cover B and in this instance is held in position 40 by means of a screen q interposed between said plug and a filler plug r screwed in the outer end of the bore p. The plug o in this instance carries at its innermost end a reduced portion s in which is formed a small 45 passage t opening into the passageway J. The rearward end of the passage t opens into an aperture u which communicates with the passage R in the spindle P through ports v in the plug o. The end wall of the aperture 50 u in the plug o is suitably tapered to form a valve seat w for a needle valve x threaded into the plug o.

Near the outer end of the bore p is formed 55 a chamber y which encircles the screen q and communicates in this instance with the reservoir F through passages z and 2 to enable oil introduced into the chamber y to pass into the reservoir F.

In the operation of the device, whenever 60 pressure fluid is admitted into the passageway J a portion thereof will flow through the passage g, port j thence through the passages Q and U and through the tube k into the reservoir F to create a pressure on the surface of the oil in the reservoir.

Owing to the pressure differential between the flared portion O and the restricted portion L of the passageway J the pressure acting on the surface of the oil will be greater than that in the restricted portion L of the passageway, 70 as a result the oil will be forced through the passage e in the pendulum Y, the passages f, T and R, thence through the ports v, the aperture u and the passage t into the restricted portion L of the passageway J. At this point 75 the oil mingles with the pressure fluid flowing through the passageway and is carried thereby to the machine intended to be oiled.

As will readily be seen, the inlet opening of the passage e in the pendulum Y may at all 80 times occupy the lowermost position in the casing A. For instance, if the casing A be so disposed that it rests on the bottom wall E the head d of the pendulum will draw that end of said pendulum against the bottom wall 85 E and consequently will elevate the outlet opening of the tube k above the surface of the oil. Due to the ability of the pendulum Y to thus adjust its position with respect to the casing A, the supply of oil in the reservoir F 90 may be completely exhausted after each refilling.

Whenever it may be desired to increase or decrease the supply of oil into the passageway, the needle valve x may be either screwed 95 into or out of the plug o to regulate the clearance between the needle valve x and the seat w. This is a desirable feature in devices of this character since it enables oils of different viscosity to be used with the same 100 device as well as the regulation of the supply for either a single machine or a plurality of machines to which the pressure fluid may be supplied.

In Figure 4 is indicated the manner in 105 which the bearing S may be assembled in the body X of the pendulum Y. The manner in which this may be accomplished is as follows: First, the bearing S may be inserted in the body X in substantially the manner indicated in the drawing and after such insertion of the bearing, said bearing may be rotated one-quarter revolution, this will place the bearing in substantially the operative position so that its curved surfaces V may co-operate with the curved surfaces in the body 110 to form a seal between these parts.

I claim:

1. An air line oiler, comprising a casing having an oil reservoir and a passageway in 120 the form of a Venturi tube for pressure fluid, a spindle supported by the casing and extending into the reservoir remote from the passageway, said casing and spindle having passages for conveying pressure fluid from the large diameter of the passageway into the reservoir and oil from the reservoir into the throat of the passageway, and a pendulum rotatable on the spindle having 125 passages in constant communication with the 130

passages in the spindle, said pendulum having a weighted portion to maintain the entrance end of one of the passages in the pendulum in the extreme lowermost point of the reservoir.

5. 2. An air line oiler, comprising a casing having an oil reservoir and a passageway in the form of a Venturi tube for pressure fluid, a spindle threaded into the casing and extending into the reservoir remote from the passageway, said casing and spindle having inlet passages for conveying pressure fluid from the large diameter of the passageway into the reservoir and outlet passages for conveying oil from the reservoir into the throat of the passageway, a bearing rotatable on the spindle having passages communicating with the passages in the spindle, and a hollow pendulum rotatable on the bearing conveying oil from the reservoir into the outlet passages and pressure fluid from the inlet passages into the reservoir to create a pressure on the oil for forcing the oil into the passageway, said pendulum having a weighted portion to insure submersion of one end of said pendulum in the oil.
3. An air line oiler, comprising a casing having an oil reservoir and a passageway for pressure fluid, a spindle threaded into the casing and extending into the reservoir, said casing and spindle having inlet passages for conveying pressure fluid from the passageway into the reservoir and outlet passages for conveying oil from the reservoir into the passageway, a bearing rotatable on the spindle having passages communicating with the passages in the spindle, a hollow pendulum rotatable on the bearing conveying oil from the reservoir into the outlet passages and pressure fluid from the inlet passages into the reservoir to create a pressure on the oil for forcing the oil into the passageway, said pendulum having a weighted portion to insure submersion of one end of said pendulum in the oil, and means adjustable in the casing for controlling the volume of oil flowing from the outlet passage into the passageway.
4. An air line oiler, comprising a casing having an oil reservoir and a passageway

for pressure fluid, said passageway being restricted intermediate its ends to create a pressure differential therein, a spindle secured to the casing and extending into the reservoir, a bearing rotatable on the spindle, 55 communicable outlet passages in the casing, the spindle and the bearing for conveying oil from the reservoir into the passageway, communicable inlet passages in the casing, the spindle and the bearing conveying pressure fluid from the passageway into the reservoir, said inlet passage having an entrance end opening into the passageway remote from the restricted portion, a pendulum rotatable on the bearing having an oil passage 60 for conveying oil to the outlet passage, and a tube on the pendulum conveying pressure fluid into the reservoir, said pendulum having a weighted portion to maintain the entrance end of the oil passage in the lowermost point 65 of the reservoir.

5. An air line oiler, comprising a casing having an oil reservoir and a passageway for pressure fluid, said passageway being restricted intermediate its ends to create a 70 pressure differential therein, a spindle secured to the casing and extending into the reservoir, a bearing rotatable on the spindle, communicable outlet passages in the casing, the spindle and the bearing for conveying oil 75 from the reservoir into the passageway, communicable inlet passages in the casing, the spindle and the bearing conveying pressure fluid from the passageway into the reservoir, said inlet passage having an entrance end opening into the passageway remote from the restricted portion, a pendulum rotatable on the bearing having an oil passage for conveying oil to the outlet passage, a tube on the pendulum conveying pressure fluid into 80 the reservoir, said pendulum having a weighted portion to maintain the entrance end of the oil passage in the lowermost point 85 of the reservoir, and a needle valve in the casing controlling the volume of oil flowing through the outlet passage into the passageway.

In testimony whereof I have signed this specification.

ARTHUR E. PETERS.
